UNITED STATES PATENT OFFICE.

CHARLES PHELPS, OF OSKALOOSA, IOWA.

SECTIONAL HOT-WATER FURNACE.

1,203,044.

Specification of Letters Patent.

Patented Oct. 31, 1916.

Application filed January 3, 1911. Serial No. 600,560.

To all whom it may concern:

Be it known that I, CHARLES PHELPS, a citizen of the United States, residing at Oskaloosa, in the county of Mahaska and 5 State of Iowa, have invented a certain new and useful Sectional Hot-Water Furnace, of which the following is a specification.

The object of my invention is to provide a furnace of this class in which one of the 10 sections, for instance, the rear one, may be made strong, and heavy to receive and support the various water pipes and the smoke flue and the other sections may be made relatively light, simple and inexpensive and may 15 be readily, easily and quickly attached to or detached from the rear section or each other as they are not subjected to strains by connecting or disconnecting water pipes with them and as there are no water pipes to be 20 unscrewed from them when they are detached.

A further object is to provide a furnace of this class in which the circulation of both the products of combustion through the 25 interior of the furnace and the water through the furnace walls is complete and thorough regardless of sections of which the furnace is constructed.

A further object is to provide improved 30 and simplified means for readily, quickly and easily connecting the furnace sections with each other, or detaching them.

A further object is to provide a furnace of this class in which, if any one of the 35 sections is injured or broken, the particular section may be readily and easily removed and the other sections moved together without the necessity of connecting or disconnecting the water circulation pipes.

40 A further object is to provide furnace sections and a grate member for each section so arranged that the grate members of all of the sections may be readily connected or disconnected without bolts or other fastening 45 devices so that each of the sections may be jointly locked by an operator at one end of the furnace.

My invention consists in certain details, in the construction, arrangement and combination 50 of the various parts of the device, whereby the objects contemplated are attained, as hereinafter more fully set forth, pointed out in my claims and illustrated in the accompanying drawings, in which:

55 Figure 1 shows a side elevation of a furnace embodying my invention. Fig. 2 shows

a front elevation of one of the central furnace sections embodying my invention, detached. Fig. 3 shows a sectional, perspective view of the rear furnace section, and an 60 intermediate section adjacent thereto. Fig. 4 shows a horizontal, sectional view through one side of a number of furnace sections and also illustrating portions of the grates connected therewith. Fig. 5 shows a detail, 65 sectional view on the line 5—5 of Fig. 2. Fig. 6 shows a vertical, sectional view illustrating a portion of the furnace front and a number of central furnace sections connected therewith to illustrate the means for connecting the rocking grate members. Fig. 7 shows a detail view of the downwardly projecting arm of one of the grate members and the adjacent ends of the links for connecting 70 said arms together, and Fig. 8 shows a detail, 75 front view of one of the projecting arms below the grates to illustrate the form of the slot or opening therein.

Referring to the accompanying drawings, I shall first describe one of the central 80 furnace sections. Each of said sections comprises two flat side members 10 of solid material having formed on its inner face a water chamber 11, said chamber being tapered toward the inner edge thereof as 85 shown in Fig. 4. Near the bottom of the side 10 the water chamber is enlarged and made rectangular in cross section as shown at 12 in Fig. 6 so that the sides of the two adjacent sections at this point are flush with 90 each other. The top surface of the part 12 at the sides of the part 11 are tapered downwardly and inwardly at 13 to thereby prevent the accumulation of ashes and dust. In each of the sides of the parts 12 I provide 95 openings in line with each other designed to receive short tapered push nipples 14, as shown in Fig. 5, for providing communication from one of the water chambers to the adjacent one. At the upper end of each side 100 of each section is a hollow rectangular water chamber 15 having openings 16 therein similar to the openings in the lower portions just described. At the top of each section between the parts 15 is a water circulating 105 chamber consisting of a flat topped member 17 and a part 18 having downwardly extending sides converging toward the bottom as shown in Fig. 3. At a point spaced below the said upper water chamber is an integral water chamber 19 communicating at 110 both ends with the water chambers 11 and

having its sides converging downwardly and toward each other. On the outer surface of each section are two lugs 20, each preferably having two bolt holes 21 therein and on the lower end of each side of each section are two lugs 22, each provided with two bolt holes 23. A supporting leg 24 is also formed on the lower end of each side of each section to rest on a suitable foundation such, 10 for instance, as that indicated at 25 in Fig.

1. Formed on the inner face of each side of each section are lugs 26 adapted to receive a grate section hereinafter described.

In order to provide for causing the products of combustion to pass close to the sides of the section and also to prevent counter-currents of the products of combustion within the furnace, I have provided at the top of each of the water chambers 19 a flat 20 deflector plate 27 with its ends spaced apart from the ends of the water chamber 19 and provided at each end with an extension 28 projected upwardly and toward the center of the furnace, its upper end being spaced 25 apart a considerable distance from the top of the furnace section. The side edges of the various plates 27 are so arranged that they will engage each other and thus prevent the passage of the products of combustion upwardly between them. Further, the side edges of the water chambers 19 of two adjacent sections are spaced apart so that the products of combustion may readily and easily pass upwardly at the ends of the 30 plates 27.

The rear section of the furnace is preferably made much stronger and heavier than the intermediate sections. Each rear section comprises a hollow body portion 29 extended 40 below the parts 12 of the intermediate sections and provided with a downwardly extended flange 30 projected below the body portion and designed to serve as an end for the ash pit of the furnace. At the top of 45 said back section is a rectangular water chamber 31 and spaced below it is a rectangular water chamber 32 substantially in line with the water chambers 19 of the intermediate sections. Between the water chambers 31 and 32 is the flue connection 33 of ordinary construction. The numeral 34 indicates a cold water pipe provided with a branch 35 and connected with the branch are the pipes 36, only one of which is shown 50 and which is connected to the hollow back section 29 at a point in line with the nipples 14. At the top of the back are the hot water pipes 37, one of which only is shown and which connects with the back at a point in 55 line with the openings 16. In this way all of the pipe connections for water and the pipe connection for the flue are connected with and supported by this strong and heavy rear section.

60 65 The section that is adapted for the fur-

nace front comprises a solid front member shaped to fit against the adjacent intermediate section and having the usual fuel door 38, ash pit door 39 and clean-out door 40. It is also preferably provided with a downwardly extended flange 41 to engage the front of the supporting wall for the furnace. It is also preferably provided with a lug 42 to which a lever 43 is attached for shaking the grate.

In each of the intermediate furnace sections is a rocking grate member 44 of ordinary construction supported in the lugs 26. Each of said grate members has a downwardly projecting arm 45. At the lower end of the arm is a slot consisting of a vertical elongated portion 46 and a lateral extension at 47 of less height vertically as shown in Fig. 8.

In order to connect these arms with each other and with the lever 43 I provide a link 48 pivoted to the lever 43 and having a notch 49 at its lower end as shown in Fig. 7. This link is of such size that it may be inserted through the slot 46 until the notch 49 is in the slot, then it may be moved laterally into the part 47 of the slot and when in this position it will be held against longitudinal movement. To prevent it from moving back into the elongated portion 46 of the slot I provide a second link 50 having at one end an oval slot 51 with a narrow opening 52 at one side. The end of the link provided with this slot may then be inserted in the elongated portion 46 of the slot in the manner indicated in Fig. 7 and turned to position at right angles, as shown by dotted lines in said figure, thus preventing the link 48 from moving into the elongated portion of the slot and also providing a connection 105 between the adjacent ends of said links and the said arm 45. In this way all of the grates may be connected with each other without the use of tools and without the use 110 of bolts, pins or other fastening devices.

In practical operation I proceed to erect my improved furnace by first placing the rear section in position and then connecting with it the various pipes for water and for the products of combustion. After this is 115 done I place the first intermediate section in position by first inserting four tapered nipples 14 in the various water connection openings between the two sections. I then press the intermediate section toward the 120 rear section until the adjacent faces of the sections are close together. In this way watertight means are formed between the circulating openings of the two sections. The other intermediate sections may then 125 be connected in the same manner. After they are placed in position I insert bolts 53 in the lugs 20 and 22 as shown in Fig. 1. These bolts serve the double function of assisting in drawing the sections together 130

and of firmly holding them when in position. The bolts are short and run from one section to the other only so that the bolts of any one section may readily, quickly and 5 easily be removed to permit the removal of any particular section without affecting the means that connect the other sections together; that is to say, if it is desired to remove a section in the middle of a furnace the 10 bolts that are connected with it may be withdrawn, then the front and rear portions of the furnace forced apart without disconnecting the sections either in front or in the rear, then the desired section may be 15 removed and the furnace reconnected without the damaged or removed section and the furnace may be placed in condition for operation in a very short time. A new section 20 may of course be replaced where the old one was removed if desired.

When a fire is made on the grate the products of combustion will all pass straight upwardly through the space between the ends of the plates 27 and the adjacent side of the 25 furnace into the chamber above the water chambers 19.

In order to prevent the products of combustion from passing straight into the flue I provide the deflector plates 28 which obviously cause the products of combustion to pass upwardly over them and into the space between the plates 28 so that there will be a direct current of the products of combustion 30 passing to the flue which will prevent said direct current from interfering with the rising currents at the sides of the furnace sections. In this way I avoid countercurrents 35 of the products of combustion such as would

be the case if the plates 28 were omitted and the direct current passing from front to rear 40 would move past the points where the rising currents passed the ends of the plates 27.

Furthermore I provide a perfect circulation of water and prevent cross currents therein by providing passageways direct for 45 the cold water from the rear through the lower ends of all of the sections and also permit a portion of this current to rise at each section and at the top of the furnace the hot water will flow rearwardly from 50 front to rear and will be joined by the rising currents of water in each side of each section.

I claim as my invention:

A sectional furnace comprising a series of 55 detachable sections, each having at its side and top water chambers arranged in communication with each other, each having a transverse intermediate water chamber, spaced from the top water chamber, plates 60 mounted on the upper central portion of the intermediate water chambers, said plates having at their ends portions inclined upwardly and toward each other, said plates overlapping said intermediate chambers, so 65 that their edges engage for maintaining a continuous upwardly opening channel through the furnace, said intermediate water chambers being of such width that flue spaces are formed at each end of the horizontal 70 portions of the plates.

Des Moines, Iowa, November 22, 1910.
CHARLES PHELPS.
